UNITED STATES PATENT OFFICE.

HARRY S. HART, OF CHICAGO, ILLINOIS, ASSIGNOR TO RODGER BALLAST CAR COMPANY, OF CHICAGO, ILLINOIS, A CORPORATION OF MAINE.

SELECTIVE-DUMP CAR.

Application filed February 12, 1927. Serial No. 167,629.

The present invention relates to dump cars, and more particularly to the type known as ballast cars, which may deposit ballast either between the rails or outside 5 of the rails, or both between the rails and outside of the rails without flooding the track.

I have illustrated my invention in a car having the usual underframe comprising a center sill and cross sills, and having between the trucks on each side of the center 10 sill, a longitudinally extending hopper with oppositely swinging inner and outer doors hinged at the apex of the hopper, said doors forming portions of the hopper bottom so that when the outer doors are swung downwardly, material may be unloaded to the outer side of the rail; when the inner doors are swung downwardly, material may be unloaded between the rails; and when all 15 doors are swung downwardly, material may be deposited both outside and inside the rails.

One of the objects of my invention is to provide a simple, economical and efficient car by means of which ballast may be deposited either between the rails or outside of the rails or both between the rails and outside the rails without flooding the tracks.

Another object of my invention is to provide a car of the type described in which the center sill is provided with means co-operating with the free edge of the downwardly swinging doors in such a manner as to prevent the discharge of material from the doors until the latter have reached a predetermined point. In the specific embodiment of my invention herein shown and described I have illustrated a baffling means which prevents discharge of material until the free edge of the door is in a position located substantially in the plane defining an angle of repose of the deposited material, the base of which angle is below the top of the rails. It is obvious, however, that such 45 baffling means may be of less extent, but having the function of preventing any leakage from the car due to the fact that the doors may not be entirely closed.

These and other objects are accomplished by means of the arrangement disclosed on the accompanying sheet of drawings, in which—

Figure 1 is a transverse sectional view of

railway dump cars embodying the principles of the present invention, and 55

Figure 2 is a view similar to Figure 1 giving a fragmentary showing of a modification of my invention.

The various novel features of the invention will be apparent from the following description and drawings, and will be particularly pointed out in the appended claims.

Referring to the drawing, it will be noted that my invention relates to a railroad dump car having side walls 2—2. The center sill 3, comprising the channels 3'—3', extends longitudinally of the car and is provided with a cope 4 which includes the sloping walls 5—5 and the downwardly extending overlapping walls 6—6. The walls 5—5 70 slope in a downward and outward direction whereby to shed the lading from above the center sill 3. Disposed along the side walls 2—2 of the car are the sloping walls 7—7 which slope downwardly and inwardly. 75 Each of the walls 5—5 and the channels 3'—3' cooperates with the corresponding wall 7 to form rigid hopper walls, which hopper walls are provided with doors which will be more specifically referred to herein-after. 80

The car 1 is supported by trucks which are not shown but which support the car by wheels riding on the rails 9—9. For the purpose of depositing lading outside the 85 rails 9—9, doors 10—10 are provided which are mounted for swinging movement about the fixed axes 11—11. Said doors 10—10 when in closed position lie in substantially the same planes as the corresponding sloping walls 7—7. Said doors 10—10 are operated by means of chains, not shown, which in turn are controlled by the shafts 13—13 90 disposed longitudinally of the car.

Depositing of lading between the tracks 95 is controlled by oppositely swinging doors 14—14 which are swingingly mounted about the axes 11—11. Said doors 14—14 are controlled by chains, not shown, which in turn are controlled by the rotatable shaft 15 disposed longitudinally of the car.

Experience has shown that in a car of this type lading, such as ballast, will begin to flow from the edges 17 of the downwardly swinging doors as soon as the doors begin 100 to open, the amount of lading thus flowing

from the doors increasing rapidly as the opening increases. Owing to the fact that these doors swing through a considerable arc, the premature discharge of the ballast 5 is likely to result in flooding of the rails and consequent derailing of the car. Furthermore, as these edges are usually attached to the operating shaft 15 by chain mechanism of some kind, it is difficult to insure 10 tight closing of both doors due to unequal stretching of the chains so that one or both of the doors may be left in a slightly open position when it is attempted to close the doors, thus causing a leakage of material as the train is moving and thus causing a loss of such lading as ballast.

In order, therefore, to provide a means which shall insure a retention of the lading until the doors have reached a predetermined point, I have provided a car of this type with baffling means cooperating with the swinging edges of the doors in such a way as to prevent discharge of the load until the doors have reached this predetermined point. It is obvious that this baffling means may be only sufficient to insure a tight closing of the doors to prevent leakage therefrom of the lading in transit or that this baffling means may be continued, 30 as I have preferred to show it, to a point where it will insure proper placing of the lading, such as ballast, between the rails.

As will be noted from an inspection of the drawing, the swinging edges of the doors 14—14 lie adjacent the bottom edge of the sill 3 when in closed position and that the sill is provided with a downwardly depending extension member 16 attached by any suitable means, such as rivets, to the 40 bottom of the channels 3' and extending longitudinally the distance of and opposite the doors 14. The arc described by the swinging edge of the doors 14—14 is indicated by the numerals 15^b—15^b which, it 45 will be noted, coincide with the arcuate faces of the depending extension 16. The edges of the doors 14—14, therefore, move through a very considerable angle before lading, such as rock ballast, will begin to 50 flow therefrom in any substantial amount. The points indicated by the numerals 15^c—15^c may be taken to represent approximately the positions of the swinging edges of doors 14—14 when a substantial flow of 55 ballast will occur from said doors. As the doors 14—14 open to a greater degree, the the lading will pile up in a greater heap and the size of said heap will be determined approximately by the lines 15^d—15^d which 60 indicate the angle of repose of rock ballast, the limits of said heap being a substantial distance below the top of the rails 9—9 on the inside of said rails. It will be understood, of course, that the angle of repose 65 will vary slightly with different kinds of

lading and with varying degrees of wetness of said lading, but, speaking generally, the maximum dimensions of the heap of lading between the tracks will be determined by the lines indicating the angle of repose of said lading, which lines are defined by the points in the arcs 15^b—15^b which represent the position of the outer edge of the doors 14—14 in which the discharge openings are first opened an extent sufficient to pass or 75 discharge ballast from the hoppers.

It will be understood, of course, that there is a slight permissible variation in the base of the triangle representing a heap of lading between the tracks. The base of said 80 triangle may be at any level below the tops of the rails so that said base is bounded by the inner surface of the rails below the tops thereof.

Disposed adjacent the inner edge of the 85 doors 14—14 are the angular portions 17—17 which provide a seat against the base of the channels 3'—3' of the center sill. The swinging edge portions 17—17 are strengthened by means of the Z-bars 18—18, 90 the doors 14—14 being strengthened transversely by angles 19—19.

Referring now to the advantages and functions of the structure disclosed in Figure 1, it will be noted that when it is desired to deposit lading outside of the rails 9—9, such deposit may be conveniently made by controlling the swinging doors 10—10 through operation of the longitudinally extending shafts 13—13. The closed 95 positions of each of the doors 10—10 are indicated in full lines and the full open position of said doors is indicated in broken lines. The speed of the car in its travel along the rails 9—9, the degree of opening 100 of the doors 10—10, and the amount of ballast within the car 1, are factors which determine the dimensions of the pile of lading deposited outside of the rails 9—9. The broken lines 20—20 indicate angles of 105 repose of lading, such as ballast, such lines being determined by the point in the arc described by the swinging edges of the doors 10—10, at which the door is at a maximum opening, and by means of the structure illustrated, the depositing of the lading may 110 be conveniently controlled so that the angle of repose will be such that the rails will not be flooded as the car moves along said rails.

When it is desired to deposit lading between the rails 9—9, this operation can be accomplished by manipulation of the doors 14—14. The extension 16 on the lower edge of the sill 3 with its arcuate faces operating with the outer edges of the doors 14—14, prevents the passage of lading until the doors have been opened to a considerable extent, that is, until said doors have been opened to such an extent that the edge of 115 120 125 130

the doors 17 will clear the lower edges of the extension 16, which, in practice will occur approximately when the swinging edges of the doors 14—14 reach the positions indicated by the numerals 15°—15°. When the doors 14—14 have reached this position, the swinging edges of said doors will have moved to such a sloping position that lading will be directed to a region approximately midway of the rails 9—9. By reason of the described construction, a maximum amount of lading may be deposited between the rails without flooding same. The angle of repose of the lading, such as rock ballast, deposited between the rails is indicated by the lines 15a—15a. It will be clear that by reason of the fact that the doors 14—14 direct lading to a medial region spaced equally from the rails 9—9 and controlled by one swinging edge of the doors as above described, the danger of flooding said rails is minimized. In service, when the car is being moved along the track, at which time flooding of the rails is most dangerous, the illustrated construction insures a maximum of safety in this regard.

Referring now to the modification shown in Figure 2, the parts are substantially the same except that the extension 16' at the base of the sill 3 is not provided with arcuate side faces but has a flange 21 at the base thereof presenting shoulders 22—22 lying in the arc or swing of the outer edge of the doors 14'—14'. The doors are provided with end seats 17'—17' similar to those shown in the modification disclosed in Figure 1, but in addition are provided with arcuate extensions 23—23 which represent the arc of swing of the doors. In this modification, it can be readily seen that the doors present a portion 23 in close relation to the shoulders 22—22 until the doors 14'—14' have been moved through a substantial arc with the same result as that effected in the structure shown in Figure 1. In this modification, the maximum open position is represented by the dotted line position of the doors.

I claim:

1. A car of the class described having a center sill, a bottom comprising an inclined swinging door, pivoted at its lower edge, said door having a free edge extending toward the center sill, and means cooperating with said free edge to prevent discharge of material from the door until the door has reached a predetermined point.

2. A car of the class described having a center sill, a bottom comprising an inclined swinging door, pivoted at its lower edge and means attached to the center sill cooperating with the free edge of the door to prevent discharge of material therefrom until the door has reached a predetermined point.

3. A car of the class described having a center sill, a substantially V-shaped hopper on each side of the center sill, doors mounted for swinging movement about longitudinally extending axes at the apexes of the hoppers, said doors extending from their axes toward the center sill, baffling means attached to the center sill and cooperating with the swinging edges of the doors to prevent discharge of material therefrom until the doors have reached a predetermined point.

4. A car of the class described having a center sill having a depending extension, a hopper and a door for said hopper cooperating with said center sill extension, during a portion of the opening movement thereof to prevent discharge from said hopper, said center sill extension and said door being of such construction that a line representing the angle of repose of the discharged ballast, drawn from the point in the arc of swing of said door that represents the maximum raised position of said door at which discharge of ballast can take place, to the ground, will lie inside the top of the rail.

5. A car of the class described having a center sill, a substantially V-shaped hopper on each side of the center sill, and doors mounted for swinging movement about longitudinally extending axes at the apexes of the hopper, said doors extending from their hinging axes toward the center sill, said center sill being of such shape and said doors being of a length sufficient to cause the swinging edges to remain adjacent a portion of said center sill during a portion of said opening movement and prevent material flowing therebetween until the edges of said doors are substantially in the planes which define the angle of repose of the deposited material resting upon a base below the tops of the rails.

6. A car of the class described having a center sill, a substantially V-shaped hopper on each side thereof, and doors mounted for swinging movement about longitudinal axes at the apexes of the hoppers, said doors extending from their hinges toward the center sill and cooperating with a portion thereof constructed according to the length of said doors so that the doors and said portions will not separate during the opening movement to pass material from said hoppers until the edges of said doors are in a position located substantially in the plane defining the angle of repose of the deposited material, the base of which angle is below the tops of the rails.

7. A car of the class described having a center sill, a substantially V-shaped hopper on each side thereof, doors mounted for swinging movement about longitudinally extending axes at the apexes of the hopper, said center sill having an extension cooper-

ating with the edge of said doors so as to maintain the discharge opening closed until the edges of said doors are in a position located substantially in the plane defining the angle of repose of the deposited material, the base of which angle is below the tops of the rails.

8. A car of the class described having a center sill, and a V-shaped hopper on each side thereof, said sill having an extension, and each hopper having a downwardly swinging door cooperating with said extension to maintain the discharge opening closed during a portion of the opening movement until the edges of said door are in a position located substantially in a plane defining the angle of repose of the deposited material, the base of which angle is below the tops of the rails.

20 9. A car of the class described, having a center sill, a depending extension on said center sill, a hopper and a door for said hopper, said door and depending extension

having cooperating portions remaining in non-opening relationship during a portion 25 of the opening movement of said door.

10. A car of the class described having a center sill, a hopper and a door for said hopper, said center sill having an arcuate portion shaped to conform to the path traversed by the free edge of said door during the opening movement thereof and said door being pivotally mounted with its free edge cooperating with said arcuate portion of said center sill.

35 11. A car of the class described having a center sill, a hopper and an inclined door for said hopper serving in addition as a shedding surface, said door and center sill having cooperating portions remaining in non-opening relationship during a portion of the opening movement of said door.

Signed at Chicago, Illinois, this 9th day of February, 1927.

HARRY S. HART.
